UNITED STATES PATENT OFFICE

OSMOND TEODORINI, OF NEW YORK, N. Y., ASSIGNOR OF ONE-FOURTH TO BEATRICE S. SPECK, OF NEW YORK, N. Y.

SHOE HEEL

Application filed July 19, 1929. Serial No. 379,387.

This invention relates to shoe heels and particularly to devices of this class composed partially or wholly of rubber or other yielding material, and the object of the invention is to provide a heel of the class specified which is so constructed as to permit of its quick attachment and detachment in connection with the heel portion of a shoe, said heel portion having means cooperating with the means of said heel to engage and lock the heel against displacement from the shoe; a further object being to provide interlocking and interengaging means on the shoe and heel which is arranged about the peripheral edges of the heel to insure the firm support of the heel in connection with the shoe; a further object being to provide means whereby the heel may be locked and unlocked in the flexing of a portion or portions of the heel in the operation of applying the same to the shoe and detaching the same therefrom; and with these and other objects in view, the invention consists in a device of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:—

Fig. 1 is a bottom plan view of a heel indicating the same attached to the heel portion of a shoe.

Fig. 2 is a partial section on the line 2—2 of Fig. 1.

Fig. 3 is a view similar to Fig. 1 with part of the construction broken away and in section and indicating the manner of attaching and detaching the heel.

Fig. 4 is a top plan view of the heel shown in Figs. 1 to 3 inclusive, detached.

Fig. 5 is a perspective view of one of a number of coupling and lock members which I employ.

Fig. 6 is a partial section on the line 6—6 of Fig. 2, on an enlarged scale; and,

Fig. 7 is a view similar to Fig. 6 showing a slight modification.

In heel devices of the class described, which are commonly known as rubber heels, it is customary and the practice to secure such heels to the heel portion of a shoe by gluing and nailing, and it is the principal object of my invention to provide a heel which when replacement is necessary, may be replaced without the use of tools, implements or fastening devices of any kind or class aside from the couplings provided in and constituting part of the heel structure so that any person having sufficient strength to flex a predetermined body portion or portions of the heel will be capable of attaching and detaching the same in a simple, quick and practical manner, and when properly applied, the heel will be firmly locked and retained in position upon the heel portion of the shoe.

In the accompanying drawings, I have indicated at 10 the heel portion of a shoe of any kind or class. As seen in the structure shown in Figs. 1 to 6 inclusive, a plurality of nails or headed pins 11 are driven into the heel portion in a definite spaced relation to each other and to the boundary walls of said heel portion and in such manner as to arrange the heads 11a of said nails in spaced relation with respect to the lower face of the heel portion 10. This is guided in the construction shown by providing a collar 11b on the shank of the nails or pins 11 inwardly of the heads 11a, and the nails or pins are preferably driven into the heel portion 10 sufficiently to imbed the collars 11b in the texture of said heel portions so as to lie flushly with the outer surface thereof as clearly seen in Fig. 6 of the drawings. As above stated, the placement of the nails or pins 11 may be guided by any suitable means as it is important that they are properly positioned with respect to the coupling members of my improved heel 12.

The heel 12 is composed of rubber or rubber composition and in fact may be composed of any suitable yielding and flexible material. These heels are molded in accordance with the conventional methods, and in forming the heels, a plurality of coupling members 13

are imbedded in the body of rubber in a spaced relation which corresponds to the spacing of the nails or pins 11 fixed to the heel portion of the shoe.

5 In the construction shown in Figs. 1 to 6 inclusive, all of the coupling members 13 are of similar form and consist of a large disk 14 arranged well within the body of rubber from which the heel 12 is formed. On one 10 surface of the disk is a protruding and substantially U-shaped body 15, the outer wall of which has an elongated aperture 16 opening outwardly through one side of said body. Arranged between the disk 14 and the lower 15 surface of the member 15 is a comparatively large chamber 17 with which the aperture 16 communicates, the outer surface of the member 15 by virtue of the aperture 16 therein forming a U-shaped flange 18 which 20 serves to engage the heads 11a of the nails 11 to retain the heel 12 against displacement from the heel portion 10. The inner surfaces 19 of the flanges 18 preferably taper to the crosshead end thereof to form a wedge-like 25 action between said flanges and the heads of the nails.

All of the couplings 13 are of similar construction, and seven of said members designated at 13a, Fig. 3 of the drawings, are 30 arranged with the apertures 16 opening toward the toe end of the shoe whereas the members designated at 13b which are disposed at the front corner portions 12a of the heel are arranged with said apertures directed 35 backwardly and outwardly at an angle of approximately forty-five degrees to the longitudinal plane of the shoe.

In molding the heel with the members 13 therein, means is provided to form at the 40 open end of the apertures 16, recesses 20 opening outwardly through the upper or inner face of the heel so as to permit the passage of the heads 11a of the nails or pins 11 into the heel sufficiently to place said heads 11a in position to engage the flanges 18 of the 45 several coupling members 13a in a forward sliding movement of the heel 12 with respect to the heel portion 10.

In accomplishing this result, the heel is 50 first placed in a position similar to that indicated in dotted lines in Fig. 2, in which position, the heads of the nails and the nails will be arranged within the recesses 20 of the members 13a only. By pressing the heel 55 in the direction of the heel portion of the shoe and sliding the same forwardly into the position shown in Fig. 2, the heel will be temporarily secured to the shoe. In this operation, two fingers of the hand may at the 60 same time force the corners 12a of the heel inwardly to bring the recesses 20a in position to engage the heads of the corresponding nails, and when the corner portions of the heel are released, the outward flexure 65 thereof will cause the heads to move into en-

gagement with the flanges 18 of the members 13b to lock the heel against accidental displacement from the shoe.

Instead of proceeding as above, the heel may be placed in position similar to that shown in full lines in Fig. 2 and each member 13b arranged at the corner portions 12a placed in operative position by flexing said corner portions 12a separately and independently by grasping the shoe and applying the thumb pressure to one or both ends of said corner portion, and then exerting slight inward pressure to engage the head of the nail with the flange.

In releasing the heel, the above operation 80 is reversed. That is to say, the corner portions 12a are flexed inwardly and pressed outwardly and when both members 13b are disengaged from their pins, slight pressure in a backward direction will move the heel into the dotted line position shown in Fig. 2 and release the same from the shoe. After one or two attempts, the operation of coupling and uncoupling the heel, especially 85 with respect to the corner portions 12a, becomes a very simple task, and by arranging the interengaging elements of the shoe and shoe heel in the manner shown or in any other desired manner, the heel becomes firmly 90 held and secured to the shoe and locked against displacement therefrom when subjected to stresses or strains of any kind or class.

It will be understood that the heel may be molded to provide any suitable contour to the inner or outer surfaces thereof, but it is 100 preferred that the inner surface be hollowed out to a slight degree as seen at 12b so that the peripheral edges will be brought into firm contact with the peripheral edges of the heel portion 10, and rings, beads or other tread surfaces 12c may be arranged on the lower or outer surface of the heel, these preferably adjacent and in alinement with the coupling members 13 or any other tread surface can be provided.

It will also be understood at this time that the shoe heel will be made up in sizes to suit the sizes of shoes in connection with which they are to be coupled and as near as possible, one conventional arrangement of spacing of the nails 11 and coupling members 13 will be provided to as many sizes as possible, it being apparent that extremely small as well as extremely large sizes will require separate spacing and arrangement as well as an increase or decrease in a number of the coupling members and nails employed. In the event of very small heels, two or three nails and members would be sufficient.

In Fig. 7 of the drawings, I have shown a slight modification wherein a nail 21 of conventional type and without the collar 11b is employed. In this construction, a coupling member 22 is employed which is similar in practically all respects to the member 13, the 125

other difference being that the recess 23 similar to the recess 17 and into which the head 21a of the nail 21 passes, opens outwardly through the device to register with a nail 5 receiving aperture 24 formed in the heel 25 in the process of molding the same. So, with this construction, the heel 25 may be applied to the heel portion of the shoe by properly positioning the same thereon and then driving 10 the nails 21 through the apertures 24 in such manner as to bring the heads 21a of said nails within the chamber 23 and in position to engage the U-shaped flanges 26 of the members 22. When secured in position, the 15 heel 25 may be removed in the same manner employed in removing the heel shown in Figs. 1 to 6 inclusive, and a new heel may be substituted by sliding engagement and flexing of the corner portions of the heel 25 in 20 the same manner as applying the heel 12.

The form of construction shown in Fig. 7 of the drawings may be found to be desirable in the initial mounting upon a shoe, of heels made according to my invention and 25 especially in replacing leather heels with my improved quickly detachable and attachable heels in the repair of shoes.

It will be understood that while I have shown certain forms of coupling members in 30 a specific arrangement within a heel structure and in like manner have shown pins or other couplings upon the heel portion of a shoe which is of specific structure, that my invention is not necessarily limited to the particular devices or means herein shown and 35 described, and various other changes in and modifications of the construction herein set out may be made within the scope of the appended claims without departing from the 40 spirit of my invention or sacrificing its advantages.

Having fully described my invention, what I claim as new and desire to secure by Letters Patent, is:

45 1. A shoe heel having a plurality of coupling members imbedded therein and accessible through one surface of the heel, said members having U-shaped flanges opening into recesses in said heel at one side and adjacent said coupling members, the flanges of a plurality of said members opening in one directional line with respect to the heel, and the flanges of another member opening in a direction angularly to the first named members.

50 2. The combination with the heel portion of a shoe having a plurality of spaced and projecting coupling elements, of a shoe heel having a plurality of coupling members imbedded therein and exposed to engage the coupling elements of said shoe by slidible engagement of the heel with respect to the shoe, means whereby the flexure of a predetermined portion of the heel will move another coupling member into engagement with 55 another coupling element on the shoe in a

plane of movement angularly with respect to said sliding movement to secure the heel against accidental displacement, means for drawing the upper surface of the heel into firm engagement with the lower surface of 70 the heel portion of the shoe, the coupling elements of the heel portion of the shoe comprising headed pins, the heads of which are arranged in spaced relation with reference to the lower surface of the shoe, and the coupling members of said heel involving U-shaped flanges adapted to interlock said headed pins.

3. The combination with a shoe heel, of a mounting plate imbedded in spaced relation and exposed outwardly through the inner surface thereof and adapted to engage projecting headed pins arranged in spaced relation on the heel portion of a shoe to secure the heel to the shoe, said shoe heel being employed with the heel portion of the shoe by engaging a plurality of said headed members with said mounting plates by sliding movement of the heel with respect to the shoe, other of said headed members being coupled 90 with said heel by flexing the heel in a direction angularly to the sliding movement thereof to lock the heel against displacement from the shoe, and said mounting plates having beveled surfaces engaging the heads of said members to firmly force the abutting faces of the heel and heel portion of the shoe together.

4. A shoe heel of the class described provided with a plurality of apertures opening 100 into recesses arranged in spaced relation on the inner surface of said heel, mounting plates imbedded in the heel adjacent said recesses and exposed through the inner surface of the heel, means on said plates for engaging headed pins supported in connection with the heel portion of the shoe, said means on a plurality of plates being disposed angularly with respect to other plates to lock the heel against 105 displacement from the shoe, and said headed pins being accessible through the apertures in said heel when the same is mounted in connection with the shoe.

In testimony that I claim the foregoing as my invention I have signed my name this 17th day of July, 1929.

OSMOND TEODORINI.
